INVENTOR.

George John Bamberger

UNITED STATES PATENT OFFICE

GEORGE JOHN BAMBERGER, OF SAND SPRINGS, OKLAHOMA

DESIGN FOR A BOUDOIR LAMP

Application filed May 25, 1931. Serial No. 39,954. Term of patent 7 years.

To all whom it may concern:

Be it known that I, GEORGE JOHN BAMBERGER, a citizen of the United States, residing at 116 West 6th Street, Sand Springs, in the county of Tulsa and State of Oklahoma, have invented a new, original, and ornamental Design for Boudoir Lamps, of which the following is a specification, reference being had to the accompanying drawings, forming part thereof.

Fig. 1 is a front elevational view of the lamp illustrating my new design, and

Fig. 2 is a side view thereof.

The lamp is generally oval in cross-section, the standard being ornamented on the front and rear sides by the design shown in detail in Figure 1. The lamp shade is polygonal in cross-section, each of the panels carrying the same ornamentation as the panels clearly shown in detail in the several views.

I claim:

The ornamental design for a boudoir lamp as shown and described.

GEORGE JOHN BAMBERGER.
